UNIVERSAL MOUNTING BACKBOARD FOR TELEPHONE INSTALLATIONS

Edmund J. Soltysik, Chicago, and Richard J. Lindeman,
Elmwood Park, Ill., assignors to Illinois Tool Works
Inc., Chicago, Ill.

Filed June 24, 1974, Ser. No. 482,215

Term of patent 14 years

Int. Cl. D13—03

U.S. Cl. D26—1 E

FIG. 1 is a front perspective view showing our new design for a universal mounting backboard for telephone installations, the unshown back being plain and unornamented;

FIG. 2 is a side elevational view of our new design, the opposite side being a mirror image of the side shown;

FIG. 3 is a sectional view taken along line 3—3 in FIG. 1 and showing our new design;

FIG. 4 is a fragmentary sectional view taken along line 4—4 in FIG. 1 and showing our new design; and

FIG. 5 is an end view of our new design, the opposite end being a mirror image of the end shown.

We claim:

The ornamental design for a universal mounting backboard for telephone installations, substantially as shown and described.
